UNITED STATES PATENT OFFICE.

LEON FRASSIER, OF PARIS, FRANCE.

LIGHT-PROJECTING DEVICE.

1,101,172.

Specification of Letters Patent. Patented June 23, 1914.

Application filed October 14, 1912. Serial No. 725,586.

To all whom it may concern:

Be it known that I, LEON FRASSIER, a citizen of the Republic of France, residing in Paris, France, have invented certain new and useful Improvements in Light-Projecting Devices, of which the following is a specification.

This invention relates to light projecting apparatus in which the source of light involves considerable radiation of heat, and particularly to apparatus for projecting views or images upon a screen, and has for its object to provide means whereby the heat radiated from the source of light may be so dissipated or disposed of as to avoid undue heating of certain portions of the apparatus, such as the usual film employed in displaying kinematograph pictures, so avoiding accidents due to the film or its associated parts catching fire, at the same time permitting the light rays to be utilized to better advantage. In apparatus of this description commonly in use the light projecting lenses employed for projecting the light rays emitted by an arc lamp or its equivalent through or upon the film or image to be depicted upon the field or screen are interposed between the source of light and a water tank with the object of reducing the intensity of the heat rays emitted by the source of light and to thus reduce the risk of fire due to the over-heating of the kinematograph film. But, this position of the optical condenser of the luminous rays between the source of light and the water tank is quite unsuitable when the primary object to be achieved is considered owing to the fact that the condensing lens collects and concentrates the heat rays emitted by the light directly upon the water tank, with the result that the water in the tank is heated more under these circumstances than would be the case if the heat rays were transmitted directly upon the water tank instead of passing through the light condenser.

Owing to the position of the condensing lens at the inner or near side of the tank in apparatus hitherto employed, it is necessary to place the luminous center a considerable distance back from the condenser and tank, in order to prevent over-heating of the water by the concentrated rays, this entailing an incomplete utilization of the light rays. Moreover with the luminous center thus located the distribution of the

light is not uniform over the entire surface of the image or film to be illuminated and experience has shown that with a weak light a reflection of the points of the carbons, in cases in which an arc lamp is employed, is visible upon the screen in the form of a dark spot which is very prejudicial to the quality and tone of the image or picture projected. All these dangers and disadvantages are overcome by the arrangement forming the subject matter of the present invention, the primary feature of which consists in causing the rays emitted from the source of light to traverse the mass of water before reaching the condenser, a compound lens concentrating the luminous rays on the images or film carrying the device to be projected. The heat rays emanating from the source of light are absorbed and dissipated therefore before passing through the condenser and are thus incapable of over-heating the film as it is wound from one reel to the other. The temperature of the luminous beam when it reaches the film under these conditions is such that the mechanism for rotating the film from one reel to the other may be stopped if desired, thus allowing the same picture of the film to remain in front of the projecting lens or aperture without danger of setting fire to the film as is now so common. Apart however from demonstrating the cooling effect of the improved arrangement, this is particularly convenient when demonstrating scientific pictures for instruction purposes where it may be desirable to have the same view or image depicted upon the screen for a considerable time, as in schools or lecture halls for instance. The arrangement of the optical condensing lens on the front of the water tank also results in permitting the source of light to be brought considerably nearer to the tank because the heat of the rays is immediately removed by the water through which these rays pass, consequently, the illuminating power of the luminous body is utilized under much better conditions.

In cases in which the image or picture is to be projected upon a screen a considerable distance from the machine and the distance between the source of light and the condensing lens is increased, a better concentration of the luminous rays in order to obtain a high efficiency may be obtained by utilizing a single lens interposed between the

source of light and the back of the cooling tank which effects this concentration of the luminous rays without unduly heating the water in the tank. In a preferred form of 5 the invention this single lens for concentrating the luminous rays is surrounded by a small tank containing water which takes up the greater portion of the heat which the luminous rays concentrated by this lens 10 carry with them, this small tank being connected to the large water tank referred to above. The lens cooled in this manner is protected from fracture by the heat but is furthermore arranged in an open chamber 15 which is traversed by a current of air which prevents the formation of steam which would be produced if the lens were placed in a closed receptacle.

Although the water in the tank is only 20 slightly heated under the conditions mentioned above, regardless of whether a simple condensing lens be employed located between the water tank and the source of light, it is advisable to maintain as complete and 25 continual circulation and cooling of this water as possible so that the same water may be employed for a considerable time.

The invention is illustrated in the accompanying drawings in which—

30 Figure 1 is a view in front elevation partly sectional of a light projecting device embodying the invention. Fig. 2 is a longitudinal sectional view on the line M M of Fig. 1.

35 Referring now to the drawings, the invention is shown as comprising a tank for circulating water arranged in front of the source of light such as an arc lamp F which is intended to illuminate the film carrying 40 the image or picture to be projected. The optical condenser K is located on the front of the tank A, that is to say on the opposite side of the tank to that on which the source of light F is located. The heat rays emitted 45 by the luminous source are absorbed by the water in the tank A before reaching the condenser. This water is kept in continuous movement and cools in the following manner.—Adjacent to each lateral face of the 50 tank a serpentine tube B is provided, the lower extremity of each of which communicates with the base of the tank by means of an internally projecting pipe a provided at its upper extremity within the tank with a 55 valve b constituted by a bronze ball for example; each serpentine B communicates at its upper end with a receiver C, these receivers, the tank A and the serpentine tubes B being filled with water. From above the 60 tank A two vertically extending tubes c project and terminate in an enlargement or chamber d located on a level somewhat higher than that of the receiver C, the base of each chamber d constituting the seat for 65 a ball valve e. Each chamber d communi-

cates on the one hand with a small expandable reservoir f located above it, the reservoirs f being in communication with the atmosphere through a suitable pipe or passage g. The chambers d also communicate 70 through openings formed in the walls thereof with the serpentine tube D the lower convolution of which abuts against a vertical tube h arranged within the interior of the reservoir C and the upper end of which is 75 provided with a valve i constituted by a ball. The two receivers C are connected at the top by a tube E, which is also connected intermediate its extremities by a vertical tube G to the compression chamber of a 80 pump P. The pump P comprises a plunger H provided with a ball valve o, the stem of the plunger terminating in an enlarged portion k constituting the pump handle.

The circulation of the water in the tank is 85 produced in the following manner.—While the film is being transferred from one film carrier to the other the tank A, the receivers C and the serpentine tubes B and D being filled with water, the luminous rays from 90 the source of light first traverse the water in the tank A, imparting their heat to the water contained in the tank A. The water which is at a higher temperature in the upper portion of the tank rises in the vertical tubes c, raises the ball valves e, passes 95 into the chambers d, descends again into the serpentine tubes D, rises again in the vertical tubes h, raises the ball valves i, passes into the receivers C and from thence passes 100 through the serpentine tubes B and the pipes a to the bottom of the tank A. This automatic thermo siphon circulation of the water, as it becomes heated, may be accelerated by a mechanical device such for instance as that constituted by the pump P in the following manner.—The plunger H of this pump being at the end of its upward stroke, the water in the tank A, the serpentine tubes B, D and the reservoirs C is at 110 atmospheric pressure, since these elements of the cooling system are in communication with the atmosphere through the passages g g on the one hand and also through the orifices uncovered by the valve o of the pump plunger H when the valve is in its normal position. When the pump plunger H is forced downward, the valve o is moved by the pressure within the pump chamber to cut off communication between the interior of this chamber and the atmosphere, and the air thus compressed is forced through the pipe G and the pipes E, E into the interior of the reservoirs C. The valves i being 115 by reason of their weight and the pressure 120 thus produced, maintained on their respective seats, the water from the receivers C is forced toward the serpentine tubes B thus 125 passing into the tank A, the heated water in the upper portion of which is forced into 130

the vertical pipes *c*; thence through the chambers *d* into the expansible reservoirs *f* the air in which escapes to the atmosphere through the outlet passages *g*, the expansible reservoirs *f* being so arranged and proportioned as to permit of a ready evacuation of the air therein contained when the pump *P* is operated.

When the pump plunger *H* is released the water contained in the reservoirs *f* redescends, owing to the difference in the level between that of the serpentine tubes *D* and these reservoirs, the water passing into the receivers *C* through the pipes *h* into the serpentine tubes *B* and from thence to the tank *A*.

It should be noted that the water in the expansible reservoirs *f* cannot pass directly into the tank *A* when the pump plunger is released owing to the pressure on the non-return ball valves *e* which under these circumstances cuts off communication between the tank *A* and the chambers *d* through the pipes *c* connecting the latter.

The compound condensing lens mounted on the front of the water tank *A* is constituted by two plano-convex lenses *O*, *O'* arranged with their convex sides adjacent to each other and secured to a fixed lens-carrier *K* by screws or the like and mounted in an annular member *I* attached to the wall of the water tank *A*. The annular member *I* also supports a glass disk *m* interposed between the plano-convex lens and the water within the tank *A*. A similar annular member is provided on the opposite side of the water tank for supporting a corresponding glass disk *m'* permitting the passage of the luminous rays across the water tank.

The simple condensing lens which is located between the water tank *A* and the source of light employed when the tank is located at some distance from the source of light as when projecting images or pictures at a considerable distance, is constituted by a single lens *J* of plano-convex form and carried by an annular member *Q* supported in a removable frame *R* which may be secured by screws or the like to the annular member *I'*. This single lens *J* is cooled on the one hand by the water in the tank and on the other hand by the water contained in a small auxiliary tank constituted by the lens carrying frame *R* and two glass disks *S*, *S'*, the small auxiliary tank communicating at the top and bottom with the tank *A* through two pipes *p*, *p'* leading to passages *g*, *g'* in the wall of the tank *A*.

Furthermore the interior of the mount carrying this lens is placed in free communication with the atmosphere by means of a number of holes *r* thus preventing the formation of steam upon the faces of the lens. This additional single lens enables the light rays emitted to be utilized with good effect

even when the lens is located at some considerable distance from the source of light and it also prevents the disfigurement of the pictures above referred to in which a reflection of the carbon points is transmitted upon the screen owing to a weak light.

It will be understood that the invention is not limited to the particular construction and arrangement of the parts herein described and illustrated as various modifications may be made without exceeding the scope of the invention.

I claim as my invention.—

1. In a kinematographic projecting apparatus, the combination of a source of light, a condensing lens, and a water-tank between said lens and source of light, adapted to absorb heat from rays emitted by said source of light, which pass on to said lens therethrough, said tank having a circulatory thermo-siphon cooling system in communication therewith, adapted to radiate heat to the atmosphere and mechanical means for producing a forced circulation through said tank and cooling system for accelerating the circulation of the water therein when necessary.

2. In a kinematographic projecting apparatus, the combination of a source of light, a condensing lens, and a water-tank between said lens and source of light, adapted to absorb heat from rays emitted by said source of light, which pass on to said lens therethrough, said tank having a circulatory thermo-siphon cooling system in communication therewith, adapted to radiate heat to the atmosphere, and an air pump for producing a forced circulation through said tank and cooling system for accelerating cooling of the water therein when necessary.

3. In a kinematographic projecting apparatus, the combination of a source of light, a condensing lens, and a water-tank between said lens and source of light, adapted to absorb heat from rays emitted by said source of light, which pass on to said lens therethrough, said tank having a circulatory thermo-siphon cooling system in communication therewith adapted to radiate heat to the atmosphere, and valves in said system for preventing back pressure in said circulatory system.

4. In a kinematographic projecting apparatus, the combination of a source of light, a condensing lens, and a water-tank between said lens and source of light adapted to absorb heat from rays emitted by said source of light which pass on to said lens therethrough, said tank having a circulatory thermo-siphon cooling system in communication therewith adapted to radiate heat to the atmosphere, mechanical means for producing a forced circulation through said tank and cooling system for accelerating the cooling of the water therein when necessary,

and valves in said system for preventing back pressure in said circulatory system.

5. In a kinematographic projecting apparatus, the combination of a source of light, a main condensing lens, a water-tank interposed between said source of light and said main condensing lens, an auxiliary condensing lens, and an auxiliary water-tank interposed between said source of light and said auxiliary lens, and a circulatory thermo-siphon cooling system in communication with said tank, said water tanks being adapted to absorb heat from the rays emitted from said source of light which pass on through said tanks to said condensers, the rays which pass through said tank which is in front of said auxiliary lens passing through said auxiliary tank without previous concentration, said auxiliary lens being located in a chamber adapted to have a circulation of air therethrough on both sides of said lens.

6. A device for use in cooling the rays from a source of light of a kinematographic projection apparatus, comprising a water tank of relatively small dimensions having a window therethrough for the passage of rays from the source of light, and heat radiating thermo-circulatory means, said means being connected to said tank and having all parts out of the path of the rays through said window.

7. A self-contained device for use in cooling the rays from a source of light in a kinematographic projection apparatus, comprising a water tank of relatively small dimensions, having a window therethrough for the passage of rays from the source of light, and a heat radiating thermo-circulatory means, said means comprising coiled pipe in contact with the air, connected to the said tank, and having all parts out of the path of the rays through said window.

8. A self-contained device for use in cooling the rays from a source of light of a kinematographic projection apparatus, comprising a water tank of relatively small dimensions, having a window therethrough for the passage of rays from the source of light, a condensing lens on the side of said tank adjacent to the source of light, and heat radiating thermo-circulatory means, said means comprising coiled pipe in contact with the air, connected to said tank, and having all parts out of the path of the rays through said window.

9. A self-contained device for use in cooling the rays from a source of light of a

kinematographic projection apparatus, comprising a water tank of relatively small dimensions, having a window therethrough for the passage of rays from the source of light, a condensing lens on the side of said tank adjacent to the source of light, said lens being exposed to air circulation on both sides thereof, and heat radiating thermo-circulatory means, said means comprising coiled pipe in contact with the air, connected to said tank, and having all parts out of the path of the rays through said window.

10. A self-contained device for use in cooling the rays from a source of light in a kinematographic projection apparatus, comprising a water tank of relatively small dimensions, having a window therethrough for the passage of rays from a source of light, and heat radiating thermo-circulatory means, said means comprising coiled pipe in contact with the air, connected to said tank, and having all parts out of the path of the rays through said window, and a small tank in the circulatory system between parts of said coiled pipe.

11. A self-contained device for use in cooling the rays from a source of light in a kinematographic projection apparatus, comprising a water tank of relatively small dimensions, having windows in the side walls thereof for the passage of rays from the source of light, and heat radiating thermo-circulatory means, said means comprising coiled pipe in contact with the air, connected to said tank, and having all parts out of the path of the rays through said window.

12. A self-contained device for use in cooling the rays from a source of light in a kinematographic projection apparatus, comprising a main water tank of relatively small dimensions, having a window therethrough for the passage of rays from the source of light, a condensing lens on the side of said tank adjacent the source of light, and an auxiliary water tank in rear of said lens, and heat radiating thermo-circulatory means, said means comprising a coiled pipe in contact with the air, connected to said main tank, and having all parts out of the path of the rays through said window.

In witness whereof, I have hereunto signed my name in the presence of two subscribing witnesses.

LEON FRASSIER.
